(57) **CLAIM**

The ornamental design for a shower rod, as shown and described.

DESCRIPTION

FIG. 1 is a perspective view of a shower rod showing my new design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is an enlarged perspective view shown broken away for clarity of illustration.

The broken lines showing mounting structure are included for the purpose of illustrating environmental structure and form no part of the claimed design.
